ELECTRIC SHAVER HOLDER

Harold L. Ettinger, Shubencadie, Nova Scotia, Canada

Filed Aug. 18, 1959, Ser. No. 57,221

Term of patent 7 years

(Cl. D4—3)

Fig. 2.

Fig. 4.

Figure 4 is a longitudinal sectional view taken on the line 4—4 of Figure 2, and with portions of the rear wall omitted for convenience of illustration.

I claim:

The ornamental design for an electric shaver holder, as shown.
